BOTTLE STERILIZER

Daniel N. Peirce, Bethayres, Pa., assignor to Fox Products Company, a corporation of Pennsylvania

Application May 10, 1937, Serial No. 141,718

7 Claims. (Cl. 21—79)

This invention relates to bottle sterilizers and it is especially useful for sterilizing milk bottles for babies. I am aware that it has heretofore been proposed to sterilize such bottles either singly or a number at a time, by means of steam generated, for example, by electrical heating members in which the water to be vaporized completes the circuit. The supporting means for the bottle or bottles, however, have been such that all of the surface is not effectively exposed to the steam, so that complete sterilization has not been obtained. Obviously nothing short of complete sterilization is satisfactory.

It is one of the primary objects of my invention to provide a device securing complete sterilization particularly of the inner surfaces and the outside of the lip and neck of the bottle.

A more specific object of the invention is to provide a device suitable for nurseries, hospitals, and the like, whereby a number of bottles may be sterilized at one time.

I also contemplate providing a unit of the character described which may be folded into compact form for shipping.

The foregoing, together with such other objects and advantages as may hereinafter appear, I accomplish by means of a construction which I have illustrated in the preferred form in the accompanying drawings, wherein—

30 Figure 1 is a partial side elevation and section (taken on the line 1—1 of Figure 2) through a unit embodying my invention and indicating the manner in which it is carried by a standard form of electrical heater.

35 Figure 2 is a plan view of the unit of Figure 1 in collapsed condition for packaging and shipping, and

Figure 3 is a side elevation of Figure 2 drawn on a smaller scale.

40 Referring now to Figure 1, the unit comprises a base member A, a handle device B therefor, and a bottle supporting means indicated as a whole by the reference numeral C adapted to be carried on the base A.

45 The base A has a central opening 7 defined by the flange 8. This flange is adapted to fit into a standard electrical heater 9 which may be of any preferred construction, known in this art. When water is introduced into the heater 9, the circuit is completed and the water converted into steam which rises through the opening 7 to ultimately sterilize the bottles, as will further appear. From a point adjacent the opening the base slopes downwardly and outwardly, terminating in an annular gutter 10 and an up-

standing rim 11, to which the handle mechanism B is secured, as will be described.

The bottle supporting means consists of an inverted pan or dome member 12, the diameter of which is such that its flange 13 will rest in the annular groove 10 when the parts are in operative position as shown. The member 12 is provided with boss-like portions 14, in number corresponding to the number of bottles to be sterilized in one operation. A cup-like member 15 is secured to the upper face of each boss. Each boss and each cup is centrally apertured and the cups are secured in any preferred manner, as by a member 16 adapted to be rolled into gripping contact, as shown in Figure 1. Rising from the member 16 is a stub tube 17 which may also be secured by rolling the member 16. The tubes are of a diameter smaller than the internal diameter of the bottle neck, small enough to avoid bridging across of the water by capillary attraction. Each cup is provided with one or more holes 18 located so that any condensate deposited in the cup will immediately discharge therefrom. The small outlet holes in the tops of the tubes insure building up sufficient pressure 20 to secure distribution of the steam among all bottles.

Bottles are placed neck down in and are centered by the cups with the neck clear of the tube and are prevented from wobbling too much 30 by the washer-like members 19 at the upper ends of the tubes 17. They are also prevented from wobbling excessively by the ring 20 secured to the handle B. Thus the bottles cannot contact with the tubes.

35 With the bottle in place and water within the heater, the steam rises into the dished member 12 and from thence through the tubes into the interior of the bottles. The bottles are filled with steam which vents itself from the bottles through the neck and into the cups, then it rises flowing over the external surfaces of the neck. The vibration occurring when the steam is being generated ensures exposure even at the line contact of neck and cup rim, this result being facilitated 40 by reason of the fact that the bottles are free to wobble. Condensate running into the cups discharges and finds its way to the annular groove 10, making a seal at that point, ensuring that all the steam thereafter must flow into the bottles. 45

The amount of water placed within the heater 9 is sufficient to secure thorough sterilization by the time that it has been completely evaporated.

Riveted to the base member 10 are a pair of forked members 21 and the handle B is in turn 55

riveted to the upper ends thereof by a single rivet 22 which permits the handle to be swung into the position shown in Figures 2 and 3. When the handle is swung to the position shown in Figure 5 1, the lip 23 spring-snaps into the notch 24 whereby the handle is held in the position shown in Figure 1. The ring 20 is riveted to the handle by single rivets so that it may be rotated to lie in the plane of the handle as shown in Figure 2. 10 Thus the device may be folded into very compact form.

When the bottles are sterilized, the unit may be lifted from the heater by means of the handle.

15 Instead of using an electrical heater, the unit may be placed in a pan of water. To this end, the flange 8 is at least sufficiently short to allow the base to rest on the gutter portion thereof. If the base be omitted, the handle is secured to the 20 dome.

20 I claim:

1. A bottle sterilizer adapted to be associated with a source of supply of steam, comprising a dome, a tube projecting upwardly from the dome 25 and adapted to deliver steam therefrom, a bottle support adapted to centralize the bottle with reference to the tube free of contact therewith and with the dome, said support being in the form of a self-discharging cup, and a base for 30 supporting the dome, said base having a peripheral gutter receiving the edge portion of the dome and having a central aperture from which the base slopes downwardly to the gutter.

2. A bottle sterilizer adapted to be associated 35 with a source of supply of steam comprising a dome, a base for supporting the dome, said base having an annular water-retaining trough receiving the edge portion of the dome, a tube projecting upwardly from the dome and adapted to 40 deliver steam therefrom, a bottle support adapted to centralize a bottle with reference to the tube free of contact therewith with the tube projecting into the neck of the bottle, said support being in the form of a cup and being adapted to 45 discharge condensate into said trough.

3. A bottle sterilizer adapted to be associated 50 with a source of supply of steam, comprising a dome, a tube projecting upwardly from the dome and adapted to deliver steam therefrom, and a bottle support adapted to cooperate with the bottle externally thereof with freedom for limited 55 wobbling movement, said tube having a washer at its upper end of larger diameter than the tube, and the bottle support and tube washer cooperating to provide against contact of the tube and bottle in the neck of the latter.

4. A bottle sterilizer comprising a base having 60 an aperture adapted to be associated with a source of supply of steam, the base having an annular trough, a dome above the base having a lip lying in said trough, a bottle support projecting upwardly from the dome and adapted to

engage a bottle at a point spaced from the mouth thereof and to support the bottle with its lip out of contact with the dome, and means for passing steam from the dome into the interior of the bottle, the bottle support being constructed to 5 provide for condensate drainage from the bottle into said trough.

5. A bottle sterilizer comprising a base having an aperture adapted to be associated with a source of supply of steam, the base having an annular trough, a dome above the base having a lip lying in said trough, a bottle support projecting upwardly from the dome and adapted to engage a bottle at a point spaced from the mouth thereof and to support the bottle with its lip out of contact with the dome, and a tube projecting upwardly from the dome into a bottle carried by 10 said support and providing for delivery of steam from the dome into the interior of the bottle, said support being in the form of a cup having 15 condensate drainage means providing for flow of condensate from the cup exteriorly of the dome into said trough.

6. A bottle sterilizer including a bottle supporting cup adapted to engage the bottle externally 25 thereof at a point spaced from its open end and to support the bottle with freedom for limited wobbling movement, a tube projecting upwardly from the bottom of the cup and providing for the delivery of steam into the interior of the 30 bottle, the tube being of substantially smaller diameter than the bottle neck, and means for restricting wobbling movement of the bottle comprising a member carried on the tube at an elevation spaced substantially above the lip of the 35 bottle and cooperating with the cup to restrict wobbling movement of the bottle sufficiently to provide against contact of the tube with the inside wall of the neck of the bottle.

7. A bottle sterilizer including a member providing a steam chamber, a generally cylindrical bottle supporting cup, the side wall of which rises from said member and is adapted to engage the outside surface of a bottle and support the same at a point spaced from the mouth of the 45 bottle with the lip out of contact with said member, and a tube rising from said member generally centrally of said cup from the bottom thereof and adapted to deliver steam from the steam chamber into the interior of the bottle, said tube being of substantially smaller diameter than the 50 inside diameter of the neck of the bottle, the bottle cooperating with the cup to substantially close the open upper end of the cup when the bottle is inserted in position to be supported in the cup to provide a substantially closed sterilizing chamber for the inner and outer surfaces 55 of the neck of the bottle, the cup having condensate drainage means adjacent the bottom thereof.

DANIEL N. PEIRCE. 60
